WIRE STRETCHER AND SPLICER

Emil Durr, Choteau, Mont.

Application June 8, 1934, Serial No. 729,707

2 Claims. (Cl. 140—123.5)

This invention relates to wire stretchers and splicers and its general object is to provide a device of that character that is capable of use with all kinds of wire, in stretching and holding the same taut and splicing the adjacent ends, in an easy and expeditious manner and with very little attention.

A further object of the invention is to provide a wire stretcher and splicer that is light in weight, yet is strong and sturdy, is simple in construction, inexpensive to manufacture and extremely efficient in use and service.

This invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views, and in which:

Figure 1 is a side elevation of my device in use.

Figure 2 is a top plan view thereof.

Figure 3 is a view illustrating the manner of completing what is generally termed a telephone splice by my device.

Figure 4 is a view showing the completed telephone splice.

Figure 5 is an end view showing the wire receiving notch of my device.

Figure 5 is a side elevation showing my device in use in making what is termed a loop splice.

Figure 7 is a top plan view of Figure 6.

Figure 8 is a view similar to Figure 3 but illustrates the use of the device in completing the loop splice.

Figure 9 is a view showing the completed loop splice.

Referring to the drawing in detail, it will be noted that the body of my device is shown as being formed from a single strip of metal that is looped midway its ends to provide what may be termed a yoke, and the body includes relatively narrow end portions indicated respectively by the reference numerals 1 and 2. The end portion 1 includes the loop which for distinction is indicated by the reference numeral 3, and the loop has arranged therein a slot 4 that follows the loop, as best shown in Figure 5 of the drawing.

The parts of the strip that make up the end portions are held in spaced relation through the instrumentality of collars 5 which are secured to the headed pins 6 that are fixed to the parts, as best shown in Figures 2 and 3.

The intermediate portion of the body is indicated by the reference numeral 7 and the parts thereof are spaced a considerable distance apart, with registering openings arranged therein to rotatably receive what may be termed a shaft 8, the latter having a handle 9 formed thereon and the shaft is held in the openings by a cotter pin or the like 10. The shaft is provided with a bore 11 that extends transversely therethrough, for a purpose which will be presently apparent.

Mounted between the parts of the end portion 2 and for rotation upon one of the pins 6 are jaw members 12 and 13 that are arranged for pivotal movement and for cooperation with each other, for the purpose of setting up clamping engagement with a strand of wire, as best shown in Figures 1 and 2. The jaw members are preferably of right angle formation and the jaw portions thereof are indicated by the reference numerals 14 and 15.

My tool is not only capable of stretching and splicing wire, but a number of different types of splices can be made therewith, and I have illustrated the manner of using the tool in making two well known splices, namely one 25 that is generally termed a telephone splice, and the other is termed a loop splice.

In making a telephone splice, one end of a strand of wire is disposed through the slot 4 and over and under the collars 5 of the end portion 1, as clearly shown in Figure 1, and the end is then inserted through the opening of the shaft 8. For distinction, this end portion of the strand of wire is indicated by the letter A. The shaft is rotated through the instrumentality of 35 its handle for winding the portion A about the shaft, until it is taut. The end portion of the strand of wire B, which is to be spliced with the strand A, is inserted between the jaw portions 14 and 15, and thence extended, and coiled about 40 the strand A as at C. The strand B is removed from the jaw portions 14 and 15, and the tool is disposed at right angles with respect to the strands, as shown in Figure 3, and rotated in a manner to coil the strand A about the strand 45 B as at D, to complete the telephone splice, as shown in Figure 4.

In making the loop splice, the end portion of a strand E of wire is passed under the loop 3 and disposed under and over the collars 5, as well as 50 inserted in the bore of the shaft 8 in the same manner as above described. Half of the loop splice is made in the end of a strand F, and the loop thereof is inserted in the slot 4, as shown in Figure 6, then the tool is arranged at right 55

angles with respect to the strand E for moving the end portion of the strand E accordingly, as shown in Figure 8, and the remaining half of the loop splice is then made to complete the splice, as shown in Figure 9.

From the above description and disclosure in the drawing, it will be obvious that I provide a wire stretcher and splicer that can be used for making many well known splices in an easy and 10 expeditious manner, and it permits the stretching of long strands of wire, due to the fact that the shaft 8 can be used for wrapping a relatively great portion of a strand thereabout, and the portion that is wrapped about the shaft can be 15 used from time to time for repairing short breaks in the wire, as will be apparent.

It is thought from the foregoing description that the advantages and novel features of my invention will be readily apparent.

20 I desire it to be understood that I may make changes in the construction and in the combination and arrangement of the several parts, provided that such changes fall within the scope of the appended claims.

25 What I claim is:

1. A wire stretcher and splicer comprising an elongated body formed from a single piece of flat material arranged in substantially yoke like formation to provide a relatively large intermediate portion and end portions extending from the intermediate portion, a shaft journalled in

the parts of the intermediate portion and bridging the same, said shaft having a bore transversely disposed therethrough to receive the end of a strand of wire so that the latter can be wrapped about the shaft, splicing means for the end portions and including collars disposed between the parts thereof, a pair of cooperating jaws pivotally mounted between the parts of one of the end portions to set up a clamping engagement with a strand of wire and the opposite end portion being provided with a slot providing a wire receiving and guiding means. 5

2. A wire stretcher and splicer comprising an elongated body formed from a single piece of flat material into substantially yoke like formation 15 to provide a relatively large intermediate portion and end portions extending therefrom, a shaft journalled in the intermediate portion and bridging the parts thereof, said shaft having a bore transversely arranged therethrough to receive 20 the end of a strand of wire, splicing means for the parts of each of the end portions and including collars acting as wire receiving means, right angled disposed wire clamping means including parallel arranged and cooperating jaws pivotally 25 secured to one of the end portions, and the opposite end portion including a loop having a slot arranged therein to act as a wire receiving and guiding means.

EMIL DURR. 30
